ATTORNEYS

UNITED STATES PATENT OFFICE.

JOHN CHRIS OLSEN, OF MINNEAPOLIS, MINNESOTA; SINEV C. OLSEN ADMINISTRATRIX
OF SAID JOHN CHRIS OLSEN, DECEASED.

CIRCUIT CLOSER.

Application filed April 7, 1920. Serial No. 371,863. Renewed September 28, 1923.

To all whom it may concern:

Be it known that I, JOHN CHRIS OLSEN, a citizen of the United States, and a resident of Minneapolis, in the county of Hennepin 5 and State of Minnesota, have invented certain new and useful Improvements in Circuit Closers, of which the following is a specification.

This invention relates to circuit closers 10 and the object of the invention is to provide a device of this character having novel means whereby a circuit is closed when the temperature drops below a predetermined point or in the event of a fire in the immediate vicinity of the device.

In the drawings:

Figure 1 is a diagrammatic view showing the device in use as a burglar alarm.

Figure 2 is a side view with parts broken 20 away of the weight and its supports.

Figure 3 is a side view showing the device in use as a frost alarm.

Figure 4 is a section on the line 4—4 of 25 Figure 3.

Figure 5 is a rear view of the base.

Figure 6 is a perspective view of the restraining means adapted to be released by heat.

The improved switch which is adapted to 30 be interposed in a normally open electrical circuit having an alarm for closing the said circuit to actuate the alarm, comprises a base 1, to which is hinged a switch arm 2 which may be of any usual or desired construction, the said arm being hinged at 3 to the base. This switch is adapted to close 35 between contact members 4 on the base, to close the circuit, as indicated in broken lines in Figures 1 and 3, and the switch arm is 40 operated by the usual handle 5.

The base 1 is adapted to be secured to a suitable fixed support by screws 6 which are passed through openings in the base, and at that end adjacent to the hinged connection 45 of the switch arm, a plate 7 is secured to the base. This plate at the base is provided with webs or flanges 8 which lap upon the opposite sides of the base.

A substantially U-shaped arm 9 is hinged 50 to the flanges 8, the arm having at each end an eye 10 which engages one end of a headed pin 11 supported by the webs or flanges 8. A coil spring 12 encircles the pin 11 between the flanges, and one end of 55 this spring indicated at 13, bears against

the arm 9, and acts normally to press said arm toward the switch arm 2. The other end of the spring engages the base 1. The plate 7 has a slot or opening 14 near its upper end for receiving the outwardly 60 curved portion 15 of a holder consisting of a body 16 and arms 17 extending from the ends thereof. The plate 7 constitutes a support for the vial holder.

The portion 15 extending from the slot 65 14 and on the opposite face of the plate 7 from the body of the holder, is adapted to receive a plug or bar 20 of fusible material to be presently described, when the device is used as a fire alarm.

Each arm 17 of the holder has an inwardly extending lug 18 at its free end, and the said lugs are notched to receive a bottle or other glass container 19 for holding water, when the device is intended for 70 75 use as a frost alarm.

When the device is used as a burglar alarm, the mechanism shown in Figures 1 and 2 is used. The said mechanism comprises a weight 21, which has at its upper 80 end a notch or rabbet 22, and the corner remote from the rabbet is rounded as shown. This weight has an opening 23 extending therethrough, and this opening is adapted to be engaged by a pin or the like, as for 85 instance, a nail 24 which is driven into the casing 25 of a door in convenient position to be engaged by the weight.

To the door there is connected an arm 26 which rests in the rabbet of the weight, 90 when the door is closed. A flexible member 27 is connected with the switch arm at one end and with the weight at the other, the flexible member having a loop passing through the opening 23, and the flexible 95 member passes over a nail or the like driven into the casing of the door, to properly guide the flexible member.

In operation as a burglar alarm, the parts are arranged as shown in Figures 1 and 2, 100 the weight being placed on the nail, with the bar 26 resting in the rabbet. It will be evident that when the door is pushed open, the weight will be dislodged from the nail, and will throw down the switch arm.

When the device is used as a frost alarm, the parts are arranged as shown in Figures 3 and 4, the bottle 19 containing water being placed in the notches of the lugs 18, and with the spring arm 9 between the bottle 110

and the body of the holder. When now the water in the bottle freezes the bottle will burst, and the arm 9 will be released. The arm 9 will strike the switch arm and will throw the same down into the broken line position of Figure 3, closing the circuit.

When the device is used as a fire alarm, the plug 20 of paraffine and wax is placed in the curved portion 15 of the holder between the said curved portion and the plate 7. The bottle 19 is also placed as shown in Figure 3. When now the plug fuses the arm 9 will be released, and will close the switch arm.

Referring to Figure 3, it will be seen that the curved portion 15 of the holder has a catch 30 which is connected to the curved portion of the holder by a drop of solder indicated at 29, the said solder being fusible at a predetermined temperature. This solder is an alternative construction taking the place of the plugs 20. Normally this catch 30 locks the holder to the element 7. When the device is used as a fire alarm, the solder will fuse at a predetermined temperature, releasing the holder which will close the circuit. The device can also be used as a fire alarm by locking the holder to the plate with the latch thirty (30), as shown in Figure three (3). When now the solder at 29 fuses the arm 9 will be released, and will close the switch arm.

I claim:

1. A device of the class described, comprising a support having an opening, a holder having a looped portion passed

through said opening, a fusible element engaging said looped portion, a liquid containing vial carried by said holder, and a spring actuated arm engaging said vial and held in a retracted position thereby.

2. A device of the class described comprising a support, a holder associated with the support, a fusible element connecting said holder to said support, a liquid containing vial carried by said holder, and a spring actuated arm engaging the said vial at a point spaced from its ends and normally held in a retracted position by said vial.

3. A device of the class described comprising a member having its intermediate portion formed with a substantially semi-circular loop, a support receiving said loop, a fusible element passing through said loop and engaged with said support whereby to connect the member to the support, and a spring actuated arm pivoted to said support, there being means establishing a connection between said arm and said member, said means consisting a a breakable vial connected at its ends to said member and having its intermediate portion engaged by said arm.

4. A device of the class described comprising a holder having inwardly directed end portions, a breakable vial connected to said end portions, a spring actuated member engaged with said breakable vial and normally held in a retracted position thereby, and fusible means normally retaining said holder in a retracted position.

JOHN CHRIS OLSEN.
